Specification for Design.

Patented Mar. 28, 1922.

Application filed January 11, 1921. Serial No. 436,573. Term of patent 7 years.

To all whom it may concern:

Be it known that I, CHARLES J. WEYMAN, a citizen of the United States of America, and resident of Wheeling, county of Ohio, and State of West Virginia, have invented a new, original, and ornamental Design for a Combined Shade Support and Curtain Hanger, of which the following is a specification, reference being had to the accompanying drawings, in which—

bined shade support and curtain hanger, illustrating my new design, and—

Figure 2 is a side elevation of the same.

I claim:

The ornamental design for a combined shade support and curtain hanger, substantially as shown.

CHARLES J. WEYMAN.
